T. CRANE.

Flour Mill.

No. 14,132.

Patented Jan. 22, 1856.

Fig. 2

UNITED STATES PATENT OFFICE.

THOMAS CRANE, OF FORT ATKINSON, WISCONSIN.

FLOURING-MILL.

Specification of Letters Patent No. 14,132, dated January 22, 1856.

To all whom it may concern:

Be it known that I, THOMAS CRANE, of Fort Atkinson, in the county of Jefferson and State of Wisconsin, have invented a new and useful Improvement in Flouring-Mills; and I do hereby declare that the following is a full and exact description thereof, reference being had to the accompanying drawings, making a part of this specification.

Figure 1, is a top view of my improved flouring mill, with the cap removed, and Fig. 2, is a vertical section in the line y, y , of Fig. 1.

Similar letters indicate like parts in both figures.

The bed-stone b , of my improved flouring mill, is inclosed within a metallic hoop p , which rises from a suitable bed-plate p' . The bed m , on which the bed stone rests, should be so proportioned as to cause the face of said stone to always be a little above the upper edge of its inclosing hoop. Between the outer surface of the inclosing hoop p , and the bed plate p' , from which it springs, there is an annular open space which communicates with a discharging spout n . An offset at one side of the said annular space, has a segment-shaped recess q , which receives the adjustable bearing boxes j, j , of the vertical journals of two rollers i, i . Two flanchered rollers f, f , are located in offsets from the annular space which surrounds the hoop p ; which offsets, are situated about equidistant from each other and from the aforesaid rollers i, i . The horizontal journals which project outward from the said rollers f, f , are received into bearing boxes g, g , which fit accurately into radial slots in the base-plate p' ,—and the outer extremities of said journals, are acted upon by set screws h, h , as shown in Fig. 2. A deep metallic hoop c , having a broad flanch d , projecting outward from its upper end, is received into the outer portion of the annular space surrounding the bed-stone inclosing-hoop p , and is supported by means of its projecting flanch d , resting upon the barrels of the rollers f, f , and the upper ends of the rollers i, i . The peripheries of the rollers i, i , bear against

the outer periphery of the hoop c , and the flanches of the rollers f, f , bear against the outer periphery of the flanch d , of the said hoop c . The set screws h, h , therefore enable the said hoop c , to be securely supported and its position adjusted between the rollers i, i , and f, f . Wings e, e , are connected to the inner periphery of the hoop c , which project inward until they are brought nearly in contact with the hoop p . A driving pulley k , is located between and a little outside of the rollers i, i , the shaft of which—driving pulley—passes down through the base plate p' and has a pulley, or cog-wheel, upon its lower end by which it is connected to any suitable machinery for imparting motion to it and to the hoop c , to which it is connected by means of the band l . A slow motion should be imparted to the hoop c, d , which will cause its wings to move the flour, or meal, discharged into the annular space surrounding bed-stone, slowly around and discharge the same, through the spout n .

It will therefore be perceived, that the aforesaid arrangement of the annular space around the bed-stone, and the winged hoop moving therein, will prevent the flour, or meal, from accumulating about the running stone and heating, at the same time that it serves in a considerable degree to cool the meal, before discharging it through the spout n .

What I claim as my invention and desire to secure by Letters Patent, is—

Securing the bed-stone within a hoop rising from a suitable bed-plate, when the said hoop has an open annular space surrounding it, which is supplied with a discharging spout and has a rotating winged hoop arranged and operating therein substantially in the manner and for the purpose herein set forth.

The above specification of my improvement in flouring mills signed and witnessed this 28th day of Decr. 1855.

THOMAS CRANE.
